DEVICE FOR DOWELING TRANSVERSE JOINTS OF CONCRETE ROAD PAVEMENTS

Alexander Musall, Berlin, Germany; vested in the Alien Property Custodian

Application March 25, 1941, Serial No. 385,177
In Germany June 5, 1939

5 Claims. (Cl. 94—17)

The invention relates to improvements in means for doweling transverse joints of concrete road pavements involving a metal plate resting perpendicularly on the formation level. In concrete road pavements it is usual to arrange between each pair of spaced joints two apparent or pressing joints, which require doweling the same as the spaced joints, so that the vertical transverse forces exerted between any two adjoining plates of a concrete pavement may be taken by the dowels, which in the apparent or pressing joints as well as in the spaced joints, are capable of yielding to the contractions and expansions or to the subsequent expansions of the plates of concrete pavements.

The object of the invention is to construct a doweling device which, apart from doweling the plates of the pavement, is adapted to form a permanent joint, requiring a small quantity of material and being simple to install, and in which the same principal elements may be used for the apparent and pressing joints as well as for the spaced joints. Accordingly, the invention principally consists in a doweling device composed of a metal plate, which is placed vertically upon the formation level, and which, in its top portion, is provided with flaps formed by vertical incisions, these flaps being bent at the top alternately to the left and to the right so as to form horizontal anchoring plates. In this shape, the device is adapted to form apparent and pressing joints, the vertical transverse forces between two adjacent concrete plates being taken by the lower portion of the vertically standing metal plate, whereas the upper flaps of this plate are yielding, owing to the incisions and the anchoring in the concrete, to any contractions and subsequent expansions of the concrete plates.

The same device may also be used for forming spaced joints, in which case, however, there is provided, parallel to the vertical metal plate, according to the width of the spaced joint, a thinner metal plate serving as a casing and extending from the bottom up to the horizontal portions of the flaps, and being attached at its upper edge to the bent flap portions at one side of the vertical plate. Those of the lower flap portions which are bent towards this side of the metal plate, are covered on the opposite side of the plate, in the vertical position of these lower flap portions, with slanting thinner metal plates, whereas, in an inclined position of these lower portions, they are covered with thinner metal plates disposed parallel to the vertical plate.

Several illustrative examples of the subject of

the invention are illustrated in the accompanying drawings, in which:

Fig. 1 is a fragmentary perspective view of a doweling device for apparent and pressing joints;

Fig. 2 is an enlarged transverse vertical cross section of the device according to Fig. 1 with a removable upper pulling iron;

Fig. 3 is a similar cross section with a covering device remaining in the concrete;

Fig. 4 is a fragmentary plan view of a doweling device for spaced joints;

Figs. 5 and 6 are cross sections taken on the lines II—II and III—III of Fig. 4;

Fig. 7 is a somewhat modified cross section of the device according to Fig. 4 with an upper covering device for concrete pavements consisting of two layers; and

Fig. 8 is an enlarged fragmentary cross section of the top portion of the doweling device according to Fig. 6.

The doweling device shown in Figs. 1 to 3 consists of a vertical metal plate 1 extending across the entire width of the concrete pavement blocks and provided with legs 2 placed upon the formation level. Out of the legs 2, which are produced by bending from the vertical plate 1, there may be stamped additional flaps 2a, bent up and serving as additional anchoring means. The upper part of the vertical metal plate 1 is formed with stampings or incisions 3 perpendicular to the formation level, so as to define form flaps 4 above the uninterrupted lower part 1a. These flaps 4 are bent intermediate their height alternately to the left and to the right in horizontal planes, and these bent off flap portions 4a and 4b are embedded in the concrete and serve as anchoring plates. In order to prevent these anchoring plates 4a and 4b from being drawn out in case of contractions of the concrete pavement blocks, the free edges of the anchor plates are bent downwardly. Furthermore, the horizontal anchor plates are provided with stamped out openings 6 so as to permit the concrete, while being deposited, to fall through these openings and fill the spaces below the anchor plates 4a and 4b.

The device described above will readily serve to produce apparent joints. For this purpose it is only necessary to make incisions in the concrete layer of the pavement above the anchor plates 4a and 4b in the direction of the metal plate 1 so that, when contractions take place, the concrete will tear only in the line above the metal plate 1.

When using the device in pressing joints, where the pavement blocks meeting at the joint are

completely separated, sheet metal strips 5 are welded onto the metal plate 1 opposite the anchor plates 4b, or strips are stamped out of the lower flap portion and bent upwardly so as to extend beyond the plates 4a and 4b. These strips 5 serve as supports for a pulling iron (Fig. 2) which is slipped on, or for a covering body (Fig. 3) which is designed to remain in the concrete. The pulling iron consists of, for example, two conical hollow metal forms 7 and 8, connected by an intermediate piece 9. This pulling iron is slipped onto the strips 5, and after the setting of the concrete, it is pulled out again. The remaining hollow space is then filled up with any known type of filling material. In the construction according to Fig. 3, there is provided a covering body which remains in the concrete. This covering body consists of a metal sheet 10 which is folded in such a manner that it may be slipped over the strips 5. The parallel walls of this metal sheet 10 are provided on the outside with small anchoring flaps 12. In the space between the parallel walls there is placed an elastic insertion 13, of for example, corrugated cardboard or the like. The space above this insert may then be filled with a grouting substance. Upon contraction of the concrete blocks, the parallel walls of the covering body will yield to the surfaces of the adjoining concrete pavement blocks. The vertical transverse forces are transferred between two adjacent concrete pavement blocks via the flaps 4 upon the lower uninterrupted portion 1a of the metal plate 1 and are taken up by the latter.

In order that the doweling plate 1, whose lower uninterrupted portion takes the vertical transverse forces between the concrete blocks, may also be used for spaced transverse joints, the lower portions 4d of the flaps, whose upper portions 4b referred to herein as anchor plates, are on the right, in Figs. 4 to 6, are disposed at an angle to the lower portion 4c, whose upper portions or anchor plates 4a are on the left, so that the width of the aperture of the angle is equal to the required width of the spaced joint. In the corner of the angle of the anchor plates 4b there is attached a thin metal sheet 14 which, for example, may be welded on. This metal sheet 14, which serves as a casing, has its lower edge spot-welded at 15 to the flap 2a of the leg 2 in such a manner that the attachment at 15 will resist the pressure during the ramming of the pavement blocks, but will tear when the concrete pavement blocks expand in consequence of heat influences. The thin metal sheet 14 lies parallel to the doweling plate 1 and to the flap portions 4c and at a distance from the doweling plate 1 equal to the width of the joint.

The metal sheet 14 forms one of the walls of the transverse spaced joint, the other wall of the joint being formed by the doweling plate 1, the flaps 4c and thin metal sheets 16. These metal sheets 16 cover the openings, which are produced in bending off the flap portions 4d, from the plane of the doweling plate 1, the metal sheets 16 being attached, for example by welding, to the doweling plate 1 opposite the metal sheet 14. Instead of individual metal sheets 16, there may be used one single thin metal sheet extending over the entire length of the doweling plate 1.

As shown in Fig. 7, the lower flap portions 4c and 4d may also be in the same plane as the doweling plate 1. In this case, the metal sheets 16 must be attached at an angle in such a manner that the flap portions 4d may move into the space between the metal sheets 16 and the doweling 70

plate 1 according to the expansions of the concrete plates and according to the width of the joint, as indicated by dotted lines. For this purpose, it is best to use one single metal sheet 16 extending over the entire length of the doweling plate.

In order to save iron and to reduce the weight, the metal sheet 14 may be omitted, in which case an elastic yielding substance of the width of the joint is connected with the doweling plate 1. For this purpose, there may be used, for example, a somewhat compressed fibre material, layers of corrugated cardboard, or the like. These materials are merely required to resist or to but 15 slightly yield to the ramming pressure when the concrete blocks are being formed, whereas they must be compressible by the pressure arising at the adjacent ends of the concrete blocks caused by expansions of the latter, to an extent required 20 by such expansions. If desired, the metal sheets 16 may be replaced by cardboard, corrugated cardboard, or the like. The elastic materials or the cardboard, etc., used instead of the metal sheets 14 and 16, may be attached, for example, by gluing, or by means of wire loops, or in any other suitable manner.

If ramming of the pavement in two layers of concrete blocks is involved, it is advantageous to shape the metal sheets 14 and 16 so that they have extensions 14a and 16a passing upwardly between each pair of anchor plates 4a and 4b (Figs. 5 and 6), or to place weak angle irons 17 and 18 on the anchor plates 4a and 4b, as shown in Figs. 7 and 8. When ramming the bottom layer, there is inserted between these angle irons or said extensions a cover, which is removed after the lower concrete layer has set. When the lower concrete layer is ready, these flaps 14a, 16a and 17, 18 serve as supports for a pulling iron, 30 which is placed between the flaps and whose height is equal to the thickness of the upper concrete layer. The pulling iron is removed after the concrete has set, and the remaining hollow space is filled with a grouting material. In order to save grouting material and to prevent foreign bodies from entering the actual doweling, there 35 may be used, instead of the pulling iron, a sheet metal device according to Fig. 7 at the top, forming a permanent part of the joint and consisting of a metal plate folded three times so as to form four parallel walls, the two inner uninterrupted walls being spaced from each other at a distance corresponding to the width of the joint and having a roof-like connection 21, whereas the two outer walls 19 and 20, leaning against the inner walls, form the joints and are provided with 40 stamped out anchoring flaps 22 which are bent off at right angles. This construction results in such an elastic connection that the walls of this device 45 will yield to the expansions and the contractions of the concrete pavement blocks without great forces being required to act on said device.

What is claimed is.

1. A doweling device for joints of road pavements, said device comprising a single plate to be arranged vertically upon the foundation bed of the pavement, said plate being formed with vertical slots starting at levels substantially spaced upwardly from the lower edge of the plate and opening through the upper edge of the plate to define bendable sections, the portions of said bendable sections extending upwardly from points located above the lower ends of said slots being bent laterally with respect to the plane of said single plate so as to define anchoring plates, that

portion of some of the bendable sections extending upwardly from the lower ends of said slots as far as said levels being bent outwardly at an upward inclination whereby the last mentioned portion and thereby the anchor plates on such bendable sections are laterally displaced out of the plane of said single plate.

2. A doweling device according to claim 1 wherein a pressure resisting plate is secured at the junction of the anchoring plates with the inclined portion of said bendable sections, said pressure resisting plate depending in spaced parallel relation to said single plate.

3. A doweling device according to claim 1 wherein a pressure resisting plate is secured at the junction of the anchoring plate and the inclined portion of said bendable sections, said pressure resisting plate depending in spaced parallel relation to said single plate, and being rupturable under expansion of the pavement.

4. A doweling device for joints of road pavements, said device comprising a single plate to be arranged vertically upon the foundation bed of

the pavement, said plate being formed with vertical slots starting at levels substantially spaced upwardly from the lower edge of the plate and opening through the upper edge of the plate to define bendable sections, the portions of said bendable sections extending upwardly from points located above the lower ends of said slots being bent laterally with respect to the plane of said single plate so as to define anchoring plates, metal plates secured to said single plate at points below the plane of some of the anchoring plates and extending to points above the plane of said anchoring plates, and a pulling iron removably associated with the portions of said metal plates extending above the plane of said anchoring plates.

5. A doweling device according to claim 1 wherein plate sections are secured to said single plate in closing relation to the openings in the single plate resulting from the lateral displacement of the portion of the bendable plates below the anchoring plates.

ALEXANDER MUSALL.
